NAUTICAL NAVIGATION LIGHT

Ronald G. Martelet, 1330 N. Central Ave., Chicago, Ill.

Filed Jan. 31, 1964, Ser. No. 78,542

Term of patent 14 years

(Cl. D48—31)

FIG. 1

FIG. 2

FIG. 5

FIG. 4

FIG. 6

FIG. 3

FIG. 1 is a perspective view of a nautical navigation light embodying my new design;

FIG. 2 is a top plan view thereof;

FIG. 3 is a bottom plan view thereof;

FIG. 4 is a side elevational view;

FIG. 5 is an elevational view of the lens end thereof, and

FIG. 6 is an elevational view of the end opposite that of FIG. 5.

The side not seen in the drawings is allochiral to that shown in FIGS. 1 and 4.

I claim:

The ornamental design for a nautical navigation light, substantially as shown and described.
